UNITED STATES PATENT OFFICE.

WILLIAM E. NICKERSON, OF CAMBRIDGE, MASSACHUSETTS, ASSIGNOR TO GILLETTE SAFETY RAZOR COMPANY, OF BOSTON, MASSACHUSETTS, A CORPORATION OF DELAWARE.

BLADE-SHARPENING MACHINE.

1,324,431.

Specification of Letters Patent.

Patented Dec. 9, 1919.

Application filed November 19, 1917. Serial No. 202,708.

To all whom it may concern:

Be it known that I, WILLIAM E. NICKERSON, a citizen of the United States, residing at Cambridge, in the county of Middlesex and State of Massachusetts, have invented certain new and useful Improvements in Blade-Sharpener Machines, of which the following is a specification.

This invention relates to blade-sharpening machines of the same general character as those shown and described in my prior Patents #1,126,839, dated Feb. 2, 1915, and #1,235,590, dated August 7, 1917, and is intended to improve on such machines in certain particulars which will hereinafter appear. The invention is herein shown and described as embodied in a machine which, like the machine of my prior Patent #1,235,590 above referred to, is adapted for rough grinding or honing the edges of Gillette safety razor blades and is fully automatic in its action, my present improvements being particularly applicable to such machines.

In the accompanying drawings, Figure 1 is a front elevation of a machine containing my improvements, as preferably constructed.

Fig. 2 is a plan view of the same.

Fig. 3 is a sectional elevation at approximately the line 3—3 in Fig. 2.

Fig. 4 is a vertical section on the line 4—4 in Fig. 2.

Fig. 5 is a vertical section on the line 5—5 in Fig. 2.

Fig. 6 is in part a side elevation and in part a central longitudinal section showing a blade-carrying arm hereinafter described; and

Fig. 7 is a detail view, mainly in section, of a paste applying device hereinafter described. Certain parts are omitted from Figs. 3 to 7 inclusive, which are drawn to a larger scale than Figs. 1 and 2.

The working parts of the machine illustrated are supported by a base plate 2 and include a grinding wheel 3 which is rotated continuously and simultaneously reciprocated in the direction of its axis, a blade-holder 4 movable upward and downward above the grinding wheel and comprising upper and lower jaws between which the blade is positioned and clamped, with the edge to be sharpened projecting beyond the holder in position to rest on the top of the

grinding wheel, and a pressure bar 5 which is movable upward and downward independently of the blade-holder and rests on the projecting edge portion of the blade while being sharpened, whereby the blade edge is caused to bear on the wheel with a predetermined pressure. The blade-holder has a stem which extends at right angles to the length of the blade and is rotatably mounted in a carrier in such manner that the blade edge to be sharpened is self-adjusting to the top of the grinding wheel, on which it rests above and parallel with the axis of the latter. The lower edge of the pressure bar is also located directly above and parallel with the axis of the grinding wheel and is rendered self-adjusting to the top surface of the blade on which it rests by pivoting it to the part which carries it on a transverse axis. Except as hereinafter described, all of the parts above referred to are constructed in substantially the same way as the corresponding parts of the machines shown in the above mentioned patents, to which reference may be made for a more detailed description.

The carrier for the blade-holder consists, in the machine illustrated, of an arm 6 pivotally mounted on a two-part bracket 7 bolted to the base plate 2, the pivoted end of the arm being forked and mounted on a pair of pins 8 fixed in the bracket 7, so as to afford a long bearing for the arm. The pivotal axis provided by the pins 8 is parallel with the axis of the grinding wheel 3 and is located in the same plane as the top of the wheel, and at its free end the arm 6 is provided with a socket which receives the stem 9 of the blade-holder and extends in such direction as to cause the projecting blade edge to be presented to the top of the wheel at an angle corresponding to the bevel desired.

Provision is made for adjusting the arm 6 with respect to its pivotal axis by inserting in each end of the forked portion of the arm a cylindrical bushing 10 eccentrically mounted on the corresponding pin 8, as shown in Fig. 5, the arm being provided with slots 11 extending radially outward from the respective bushings and with a bolt 12 passing transversely through each slot and provided with a nut 13 whereby the bushings 10 may be loosened for adjustment and immovably clamped in the

arm after adjustment. It will be evident that by turning the bushings 10 in the arm 6 the latter may be moved slightly upward or downward with respect to its pivotal axis 5 to adjust the angle at which the blade edge is presented to the grinding wheel 3, and that by turning one bushing to a slightly greater extent than the other the blade-holding jaws may be skewed laterally to 10 adjust the alinement of the blade-edge with respect to the axis of the wheel. After such adjustments have been made, the blade edge may be brought directly over the axis of the grinding wheel by shifting the bracket 7 laterally on the base plate 2, such shifting being provided for by elongating the perforations in the bracket 7 which receive the bolts 14 by which the bracket is clamped to the base-plate 2, as shown in 15 dotted lines in Fig. 2. Each bushing 10 is preferably provided with a supplementary perforation 15 adapted to receive the corresponding pivot pin 8 and having a somewhat greater eccentricity than the perforation 20 in which the pin is shown as located, in order that the range of adjustment of the arm may be increased if desired.

The carrier for the pressure bar 5 consists of an arm 16 having a forked end 25 located just inside of the forked end portions of the arm 6 and pivotally mounted on the pins 8, so that the pivotal axes of the two arms are identical. From its pivotal end the arm 16 extends laterally and 30 upward to a point above the grinding wheel 3, where it is provided with a fixed head 17, and from the head 17 on its outer side a pin 18 projects at right angles to the axis of the grinding wheel and has a plate 19 pivotally mounted on it. The pressure bar 5 is pivotally mounted on a pin 20 passing through the plate 19 near its lower end and parallel with the pin 18, and above the upper end of the plate 19 are located two vertical thumb screws 21 carried by the head 17, one on each side of the pivotal axis of said plate, so that by adjusting one of the screws upward and the other downward 35 the plate can be tilted slightly and thereby caused to swing the pressure bar as a whole in the direction of the axis of the grinding wheel. The purpose of this adjustment is to locate the lower edge of the pressure bar 40 symmetrically with respect to the length of the blade edge beneath it, on which it is caused to exert the desired pressure by applying weights (not shown) to a vertical pin 22 carried by the arm 16.

The automatic raising and lowering of 45 the pressure bar and blade-holder are accomplished as follows:—

The arm 13 which carries the pressure bar is provided near its free end with a perforation 23, Fig. 3, which receives loosely 50 one end of a lever 24 having its other end

loosely mounted in the perforated upper end of a fixed upright 25 carried by the bracket 7, and to the lever 24 between its ends is pivoted the lower end of a pull-rod 26 extending upward to a suitable automatic operating and timing mechanism, such for example, as the overhead mechanism shown and described in my prior patent #1,235,590. The arm 16 may also be lifted at any time by the operator, if desired, by 55 means of a forwardly extending handle 27 secured thereto. The connections between the ends of the lever 24 and the arm 16 and upright 25 constitute a species of universal joint, so that the free end of the arm can move upward in its curved path without restraint, and the looseness of the connection between said arm and the corresponding end of the lever 24 insures the application of the full weight of the arm for 60 holding the pressure bar upon the blade when the pull-rod is lowered to the position shown in Fig. 3.

The arm 6 which carries the blade-holder is raised and lowered by means of a link 65 28 connecting the under side of the arm to the free end of an arm 29 secured to the front end of a rock shaft 30, Figs. 2 and 4, to the rear end of which is secured another arm 31 pivotally connected to the 70 lower end of a pull-rod 32 which extends upward to the overhead operating and timing mechanism above referred to. The rock shaft 30 is journaled in uprights 33 and 34 carried by a sleeve 35 which is fixed to and 75 extends forwardly from the bracket 7. A lateral extension of the front upright 33 carries a vertically adjustable rod 36 having a forwardly projecting upper end which is located above a lug 37 on the arm 6 and 80 serves as a stop to limit the upward movement of said arm, and provision is made for lowering the pull-rod 32 slightly below the point at which the blade edge to be sharpened comes in contact with the grinding wheel 3 by including a loose connection at 85 some point in the arm-lifting mechanism. For example, at the lower end of the link 28 there is shown in Fig. 1, in dotted lines, a 90 vertically elongated slot 38 which receives the pivot whereby said link is connected to the arm 29 and permits the latter arm to be lowered slightly after the blade edge rests on the top of the wheel. The pull-rod 95 39 extending upward from the arm 6 between its ends, as shown in Fig. 1, is for the purpose of connecting the arm to a pick-up weight adapted to balance the weight of the 100 arm and the parts carried thereby at the instant when the blade edge reaches the 105 grinding wheel, as explained in the above 110 mentioned Patent #1,235,590.

The jaws of the blade-holder are opened by means of a link 40 pivoted at one end to an upwardly extending projection 41 on 115

the upper jaw of the blade-holder and at its other end to a bell crank lever 42 pivotally supported on the arm 6 and connected by means of a link 43 to one end of a laterally extending arm 44. At its opposite end this arm 44 is secured to a rock shaft 45 journaled in the sleeve 35 and carrying at its rear end a laterally extending arm 46 connected by a pull-rod 47 to the overhead mechanism. The link 43 extends upward and downward in close proximity to the axis of the arm 6, so that the pivotal movements of said arm have no effect on the opening and closing of the blade-holder, 15 and vice-versa, and a loose connection similar to that at the lower end of the link 28 is provided at some convenient point, as at the lower end of the link 43, for example, thereby enabling the pull-rod 47 to be lowered far enough to insure the closing of the 20 blade-holder jaws by the springs included in the blade-holder for that purpose. The link 40 moves in a vertical slot in a lug 48 carried by the arm 6, whereby the blade- 25 holder is prevented from being rotated except to the slight extent necessary to render it self-adjusting to the top of the wheel 3.

When the machine is used for honing blade edges the grinding wheel 3 has to be 30 dressed from time to time with an abrasive paste, and provision is made for doing this automatically by means of a cup 49 attached at its center to the upper end of a downwardly-extending stem 50 rotatably mounted 35 in and supported by a tubular socket 51 carried by the free end of an arm 52 which is mounted on the reduced front end of the rock shaft 45 and is adapted to turn freely thereon, as shown in Figs. 1 and 4. The 40 cup 49 is located beneath the grinding wheel 3 and carries an upwardly-extending stick of hard paste 53 suitable for dressing the wheel and adapted to be moved into and out of contact with the cylindrical surface of 45 the latter by raising and lowering the arm 52. The stem 50 which carries the cup is inclined at a slight angle to the axis of the wheel 3, as shown in Fig. 7, and consequently when the upper end of the paste stick 53 is raised into contact with the wheel the rotation of the latter causes the paste stick and the cup to rotate also, so that the paste stick is worn down uniformly on all sides. The paste is also distributed on the 55 cylindrical surface of the wheel 3 by reason of the combined rotation and axial reciprocation of the latter, which brings all parts of its operative surface into contact with the paste stick while the latter is held in 60 elevated position.

For lifting the arm 52 to bring about the dressing of the wheel 3, as above described, I employ a tension spring 54 connecting an upwardly-projecting extension of said arm

to the bracket 7, as shown in Fig. 1, so that 65 the paste stick is elevated by the spring 54 whenever such movement is permitted. The arm 52 is normally held in its lowered position, however, by means of another arm 55 pivotally mounted on a fixed stud 56 and 70 carrying at its free end a pin 57 which overlies the arm 52, the arm 55 being acted upon by a spring 58 which tends to depress the pin 57 and is strong enough to overcome the effect of the spring 54. The arm 55 is automatically elevated against the action of the spring 58 by means of an arm 59 connected at one end to the hub of the arm 55 and at its other end to a pull-rod 60 which extends upward to the overhead mechanism, the 75 latter being arranged to lift the arm 59 at such intervals as may be necessary for properly dressing the wheel 3. The normal position of the cup 49 may be varied from time to time, according to the length of the paste 80 stick, by providing the arm 59 with a series of perforations 61, into any one of which the lower end of the pull-rod 60 can be hooked.

At the left hand end of Fig. 1 there is 85 illustrated in part, in dotted lines, a blade-transferring mechanism like that shown and described in my prior Patent #1,235,590, one of the functions of which is to reverse the blades end for end with respect to the blade-holder. This is done by means of a 90 rotatable spindle carrying at one end a pair of jaws which embrace the blade after the blade-holder has been elevated above the grinding wheel and then grasp the blade in such position that the axis of the spindle 100 passes through the center of the blade at right angles to the length of the latter, whereupon the blade-holder is lowered to disengage it from the blade, the spindle is given a half rotation to reverse the blade, 105 and the blade-holder is then elevated to receive the blade when freed from the jaws, a similar mechanism being employed for reversing the blade edge for edge in case it has two cutting edges. In the patented machine, however, the blade is slanted transversely at a fixed angle in all positions of the blade-holder, and consequently when the blade-holder is elevated to the position in 110 which the reversing jaws embrace the edge portion of the blade the first effect of the jaws on the blade when they grasp the latter is to lift it slightly with respect to the positioning pins. The result is that the control 115 of the blade by these pins is lost before the blade is tightly gripped, and hence the blade is liable to slip slightly out of position with respect to the jaws. This is detrimental to the subsequent control of the blade, since any displacement which it undergoes is doubled when it is reversed by the half-rotation of the jaws. The disadvantage just referred to is avoided in the machine herein 120 125

described, in which the parts can be so adjusted that when the blade-holder is elevated to its uppermost position the blade (shown at 62) will lie in a horizontal plane, in position to be embraced by the jaws of the reversing mechanism and tightly gripped thereby without lifting it from the positioning pins in the blade-holder.

Further advantages of the mechanism herein described reside in its simplicity as compared with that employed in the machines shown in my prior patents, the parallel-motion linkages found in the latter being omitted from the present machine, and in the effectiveness with which the relation of the blade edge to be ground and of the bottom edge of the pressure bar to the axis of the grinding wheel, and to each other, can be maintained after adjustment. This is an important factor in securing uniformity in the sharpened blade edges, and is due in part to the reduction of the number of relatively movable elements and pivotal connections in the parts which carry the blade-holder and the pressure bar, and in part to the special construction and arrangement of the means employed for adjusting these parts, all of which features contribute to the prevention of disturbance of the relation above referred to, either by wear resulting from continued use of the machine or by changes in adjustment due to accident or carelessness on the part of the operator.

The arrangement for dressing the wheel 3 is not claimed herein, as it forms the subject-matter of a divisional application filed on the 28th day of October, 1919, Serial No. 334,081. It will be evident that this arrangement, which will not be needed in case 40 the machine is used for rough grinding the blade edges, can be omitted or thrown out of action without affecting the operation of the remaining parts, and that the details of construction and arrangement of the mechanism can be modified in various ways without departing from my invention.

I claim:

1. In a blade-sharpening machine, the combination of a grinding wheel, a pivotally mounted arm, a blade holder carried thereby, and means for adjusting the arm on its pivotal axis to vary the position of the blade holder with respect to the wheel.

2. In a blade-sharpening machine, the combination of a grinding wheel, a pivotally mounted arm having a pair of spaced bearings, a blade holder carried thereby, and means for independently adjusting said bearings to vary the position of the blade holder with respect to the wheel.

3. In a blade-sharpening machine, the combination of a grinding wheel, an arm provided with a pair of spaced bushings eccentrically mounted on a common axis and independently adjustable circumferentially

with respect to the arm, and a blade holder carried by said arm.

4. In a blade-sharpening machine, the combination of a base plate, a grinding wheel mounted thereon, a bracket carried by the base plate and adjustable toward and away from the axis of the wheel, an arm carried by said bracket and provided with a pair of spaced bushings eccentrically mounted on a common axis, said bushings being independently adjustable circumferentially with respect to the arm, and a blade holder carried by said arm.

5. A blade-sharpening machine comprising a grinding wheel and a pivotally mounted arm each having a horizontal axis, a blade holder carried by the arm above the grinding wheel and arranged to hold a blade in a slanting position with respect to the wheel when presented thereto, and means for raising and lowering the arm, in combination with automatic blade-manipulating mechanism located in position to grasp the blade when presented by the holder in a horizontal plane.

6. A blade sharpening machine comprising a grinding wheel and a pivotally mounted arm each having a horizontal axis, a blade holder carried by the arm above the grinding wheel and including a blade supporting jaw adapted to hold a blade in a slanting position with respect to the wheel when presented thereto, blade-positioning devices carried by said jaw and extending upwardly therefrom, and means for raising and lowering the arm, in combination with automatic blade-manipulating mechanism located in position to grasp a projecting edge of the blade while presented by the holder in a horizontal plane.

7. In a blade-sharpening machine, the combination of a grinding wheel, an arm pivotally mounted on an axis lying in the same plane as the top of the wheel, parallel with the axis of the latter, a blade holder pivotally mounted on the arm with its axis inclined to said plane and extending transversely to the axes of the wheel and the arm, and means for adjusting the arm on its pivotal axis to vary the position of the blade holder with respect to the wheel.

8. In a blade-sharpening machine, the combination of a grinding wheel, a pair of arms pivotally mounted on a common axis lying in the same plane as the top of the wheel, parallel with the axis of the latter, said arms being movable upward and downward independently of each other, a blade holder pivotally mounted on one of the arms with its axis inclined to said plane and extending transversely to the axes of the wheel and the arms, and a self-aligning pressure bar carried by the other arm and extending lengthwise of the wheel directly above the latter.

9. In a blade-sharpening machine, the combination of a grinding wheel, a pair of arms pivotally mounted on a common axis and movable upward and downward independently of each other, a self-aligning blade-holder mounted on one of the arms above the grinding wheel, means for adjusting the latter arm with respect to its axis to vary the position of the blade holder with respect to the wheel, a self-aligning pressure bar carried by the other arm and extending lengthwise of the wheel above the blade holder, and means for adjusting the pressure bar in the direction of its length.
10. In a blade-sharpening machine, the combination of a grinding wheel, a pair of fixed pivot pins located in alinement with each other, parallel with the axis of the wheel, an arm provided with a pair of bushings eccentrically mounted on said pins respectively, and independently adjustable with respect to the arm, a self-aligning blade holder mounted on said arm and located above the grinding wheel, another arm pivotally mounted on said pins, a self-aligning pressure bar carried by the latter arm and extending lengthwise of the wheel above the blade holder, and means for adjusting the pressure bar in the direction of its length.
11. In a blade-sharpening machine, the combination with a grinding wheel and a blade holder movable toward and away from the wheel and arranged to present the edge of a blade thereto, of a support movable toward and away from the wheel and blade holder independently of the latter, a plate pivotally mounted on said support with its axis extending transversely to the axis of the wheel, a self-aligning pressure bar carried by said plate and extending lengthwise of the wheel, and means for adjusting said
- plate on its pivotal axis to vary the longitudinal position of the pressure bar.
12. In a blade-sharpening machine, the combination with a grinding wheel and a blade holder movable toward and away from the wheel and arranged to present the edge of a blade thereto, of a pivotally mounted arm movable toward and away from the wheel and blade holder independently of the latter, a plate pivotally mounted on said arm with its axis extending transversely to the axis of the wheel, a self-aligning pressure bar carried by said plate and extending lengthwise of the wheel, and a pair of adjusting screws carried by said arm and arranged to bear on the edge of the plate on opposite sides of its pivotal axis.
13. In a blade-sharpening machine, the combination of a grinding wheel, a pivotally mounted arm, a blade holder carried by the arm and having a pair of hinged jaws with springs for closing the same, and means for opening the jaws comprising a linkage carried in part by the arm and extending in close proximity to the pivotal axis of the latter, with a lost-motion connection included in the linkage to insure the closing of the jaws.
14. In a blade-sharpening machine, the combination with a grinding wheel and a blade holder movable upward and downward with respect to the wheel and arranged to present the edge of a blade thereto, of a pivotally mounted arm, a pressure bar carried thereby and movable upward and downward with respect to the blade holder and wheel above the same, and a lever having a loose connection with said arm for raising and lowering the pressure bar.

Signed at Boston, Mass., this 16th day of November, 1917.

WILLIAM E. NICKERSON.
